RAILWAY SIGNALING

George R. Pflasterer, Greenville, Pa., assignor to
The Union Switch and Signal Company, Swiss-
vale, Pa., a corporation of Pennsylvania

Application March 26, 1943, Serial No. 480,598

8 Claims. (Cl. 246—114)

My invention relates to railway signaling, and particularly to signaling for the control of traffic movements along intersecting tracks. More specifically, my invention relates to means for providing distinctive signal indications for each of two intersecting tracks, while occupied by a train adjacent the intersection, if the other of the two intersecting tracks is not occupied by a train within a given zone adjacent the intersection.

One feature of my invention is the provision of means for controlling signals for each of two intersecting tracks to display intermittent or flashing indications while their track is occupied by a train adjacent the intersection, if the other track is not occupied within a given zone adjacent the intersection, and for at other times controlling these signals to display steady indications.

I shall describe one form of apparatus embodying my invention, and shall then point out the novel features thereof in claims.

In the accompanying drawings, Figs. 1A to 1C, inclusive, are diagrammatic views showing one form of apparatus embodying my invention, in which Fig. 1A shows two intersecting railway tracks X and Z with four signals for each track, two on each side of the intersection, for governing traffic movements in opposite directions over the intersection; Fig. 1B shows circuits for controlling signal control relays; and Fig. 1C shows circuits for controlling traffic control relays and also operating circuits for the signals.

Similar reference characters refer to similar parts in each of the views.

In each of the views, the contacts operated by the various relays are identified by numbers, such numbers having distinguishing prefixes from which they are separated by a dash when the contacts are shown apart from the relay by which they are operated. The prefix for each of these contact numbers comprises the reference character for the respective relay by which the associated contact is operated. For example, contact 3H—31, shown adjacent the symbol for relay 1H in the upper left-hand portion of Fig. 1B, is identified by the number 31 separated by a dash from the prefix 3H which is the reference character for relay 3H by which this contact is operated.

Referring first to Fig. 1A, two intersecting railway tracks, designated by the reference characters X and Z, are divided into sections by insulated joints 9. Track X is divided into sections A2T, 2T, 1T, 4T and A4T, and track Z is divided into sections A8T, 8T, 5T, 6T and A6T. A track battery 10 is connected across the rails adjacent

one end of each section, and a track relay designated by a reference character which includes the letter R with a distinguishing prefix, which is the same as the reference character for the associated track section except including the letter R instead of the letter T, is connected across the rails adjacent the opposite end of each section. Sections A2T and 2T will be referred to as approach track sections for signal 1. Other track sections, similarly located with respect to signals 3, 5 and 7, will also be known as approach track sections for the corresponding signals. A relay 1AR, controlled by the approach track section relays which are associated with signal 1, will be referred to as the approach relay for signal 1. Relays 3AR, 5AR and 7AR are controlled similarly to relay 1AR, and serve as the approach relays for signals 3, 5 and 7, respectively.

Signals designated by the reference characters 1 and 3 are located adjacent the ends of section 1T for governing traffic movements in opposite directions on track X across the intersection of the two tracks. Signals 2 and 4 serve as distant signals for signals 1 and 3, respectively. Signals 5 and 7 are located adjacent the ends of track section 5T for governing traffic movements in opposite directions on track Z across the intersection of the two tracks. Signals 6 and 8 serve as distant signals for signals 5 and 7, respectively. As here shown, each of the signals is of the color light type, each of the signals 1, 3, 5 and 7 having a green or proceed lamp G, and a red or stop lamp R, and each of the signals 2, 4, 6 and 8 having a green or proceed lamp G, a yellow or caution lamp Y, and a red or stop lamp R, but may be of any other suitable design.

I shall assume that traffic movements toward the right on track X, as shown in the drawings, are eastbound, and that traffic movements toward the right on track Z, as shown in the drawings, are northbound.

Referring now to Fig. 1B, circuits are here shown for energizing signal control relays 1H, 2H, 3H, 5H and 7H for signals 1, 2, 3, 5 and 7, respectively. Relays 4H, 6H and 8H for signals 4, 6 and 8, respectively, are controlled similarly to relay 2H, and the circuits for these relays are therefore omitted from the drawings.

In Fig. 1C, control circuits are provided for energizing traffic control devices shown as traffic relays 1F, 2F, 3F, 4F and 7F. Each of these relays is energized by a control circuit including a back contact of its own, and will therefore be intermittently energized each time

its back contact is closed while its control circuit is closed. Other traffic relays 5F, 6F and 8F are energized in multiple with relay 1F, similarly to the manner in which relays 2F, 3F and 4F are shown energized in multiple with relay 1F, and are therefore omitted from the drawings.

Operating circuits for signals 1, 2, 3, 4 and 7 are shown controlled by signal control relays 1H, 2H, 3H, 4H and 7H, respectively, and including back contacts of relays 1F, 2F, 3F, 4F and 1F, respectively. Signals 5, 6 and 8 are similarly controlled by relays 5H, 6H and 8H, respectively, and by relays 5F, 6F and 8F, respectively, and therefore the operating circuits for these signals are omitted from the drawings.

As shown in the drawings, all parts are in the normal condition, that is, each of the track sections is unoccupied, and hence the track relays are energized; the red or stop lamp R for each of the signals 1, 3, 5 and 7, and the yellow or caution lamp Y for each of the signals 2, 4, 6 and 8 are lighted; relays 1AR, 3AR, 5AR and 7AR are energized; relays 2H, 4H, 6H and 8H are energized by current of reverse polarity; and relays 1H, 3H, 5H, 7H and 1F to 8F inclusive, are deenergized.

With the track relays A2R and 2R energized, approach relay 1AR is energized by a circuit passing from terminal B of a suitable source of current, through contacts 11 and 12 of relays A2R and 2R, respectively, and the winding of relay 1AR to terminal 0 of the same source of current. Relays 3AR, 5AR and 7AR are energized by similar circuits controlled by corresponding approach track section relays.

With relay 1H deenergized, relay 2H is energized in the reverse direction by current passing from terminal B, through the back point of contact 19 of relay 1H, winding of relay 2H, contact 2R-18 and the back point of contact 17 of relay 1H to terminal 0. Relays 4H, 6H and 8H for controlling signals 4, 6 and 8 are controlled by relays 3H, 5H and 7H similarly to the manner in which relay 2H is controlled by relay 1H, and are therefore not shown in the drawings.

With relays 1F and 1H deenergized, red lamp R of signal 1 is energized by a circuit passing from terminal B, through contact 20 of relay 1F, back point of contact 1H-21, and lamp R of signal 1 to terminal 0. The red lamps R of signals 3, 5 and 7 are similarly lighted. With relay 2F deenergized and relay 2H energized in the reverse direction, the yellow or caution lamp Y of signal 2 is lighted by a circuit passing from terminal B, through contact 22 of relay 2F, front point of contact 2H-23, contact 2H-24 closed in the reverse or right-hand position, and lamp Y of signal 2 to terminal 0. The yellow lamps of signals 4, 6 and 8 are similarly lighted.

I shall assume that an eastbound train on track X enters section A2T, deenergizing relay A2R. Contact 11 of relay A2R will therefore open, and relay 1AR will become deenergized. Relay 1AR, upon becoming deenergized, completes a circuit for energizing relay 1H, this circuit passing from terminal B, through contacts 5H-25, 7H-26, 5R-27, 1R-28, front point of contact 3AR-29, back point of contact 1AR-30, contact 3H-31, and the winding of relay 1H to terminal 0. With relay 1H energized, red lamp R of signal 1 will become deenergized, and a circuit will be completed for energizing green lamp G of signal 1, passing from terminal B, through contact 20 of relay 1F, front point of contact 1H-21, and lamp G of signal 1 to terminal 0.

With relay 1H energized, relay 2H will be energized by current of normal polarity by a circuit which is the same as the circuit previously traced for this relay except including the front points of contacts 17 and 19 of relay 1H instead of the back points of these contacts. With relay 2H energized by current of normal polarity, yellow lamp Y of signal 2 will become deenergized, and a circuit will be completed for lighting green lamp G of signal 2, this circuit passing from terminal B, through contact 22 of relay 2F, front point of contact 2H-23, contact 2H-24 closed in the normal or left-hand position, and lamp G of signal 2 to terminal 0.

With relay 1AR deenergized, a circuit is also completed for energizing relay 1F, passing from terminal B, through contacts 1AR-32, 5AR-35, 7AR-36, 5R-37, contact 38 of relay 1F, and the winding of relay 1F to terminal 0. Since contact 38 of relay 1F is included in its own energizing circuit, relay 1F, upon becoming energized and opening its contact 38, will thereby open its own energizing circuit, causing its back contact to again become closed and repeat the energizing operation.

Accordingly, also contact 20 of relay 1F will alternately open and close, and will thus cause lamp G of signal 1 to display a flashing indication. Relays 2F, 3F and 4F will be energized similarly to relay 1F, and will therefore similarly cause lamp G of signal 2, lamp R of signal 3, and lamp Y of signal 4, respectively, to display flashing indications.

When the train enters section 2T, relay 2R will become deenergized, and hence contact 2R-18 will open the circuit for relay 2H, causing relay 2H to become deenergized. With relay 2H deenergized, a circuit will be completed for red lamp R of signal 2, passing from terminal B, through contact 22 of relay 2F, back point of contact 2H-23, and lamp R of signal 2 to terminal 0, causing lamp R of signal 2 to display a flashing indication.

When the train enters section 1T, contact 1R-28 will open the circuit for relay 1H, causing lamp R of signal 1 to now display a flashing indication. Also, when the train enters section 1T, causing relay 1R to become deenergized, contact 1R-34 will be closed in multiple with contact 1AR-32 in the circuits previously described for relays 1F to 4F, inclusive.

When the train enters section 4T, relay 4R will become deenergized and hence its contact 13 will open the circuit for relay 3AR, causing this relay to be deenergized. Contact 3AR-33 will then be closed in multiple with contact 1R-34 in the circuits previously described for relays 1F to 4F.

When the train leaves section 2T, contact 2R-18 will again close the reverse energizing circuit for relay 2H, causing signal 2 to now display a flashing yellow indication.

I shall now assume that all parts of the apparatus are again in the normal condition, and that an eastbound train on track X enters section A2T, and that a northbound train on track Z then enters section A8T, causing relay A8R to become deenergized. The circuit for relay 7AR will thus be opened by contact 15 of relay A8R, causing relay 7AR to become deenergized.

On account of the train on track X having entered section A2T before the train on track Z enters section A8T, relay 1H will be energized, and hence its contact 1H-40 in the circuit for

relay 7H will be open, and relay 7H cannot become energized even though the back point of contact 1AR-45 is closed. With relay 1AR de-energized, contact 1AR-36 will open the circuits previously described for relays 1F to 4F, causing these relays to become deenergized. With relay 1F deenergized, lamp G of signal 1 will now display a steady indication. With relay 2F deenergized, lamp G of signal 2 will also display a steady indication. With relays 3F and 4F deenergized, signals 3 and 4 will display steady red and yellow indications, respectively.

With relay 1AR deenergized, relay 1F will be deenergized because contact 1AR-51 will be open, and will remain deenergized when the train on track X enters section 1T, on account of contact 1R-52 then being open, and will still remain deenergized when the train on track X enters section 4T, on account of contact 3AR-50 then being open. Lamp R of signal 1 will therefore be energized by a circuit passing from terminal B, through contact 54 of relay 1F, back point of contact 7H-55, and lamp R of signal 1 to terminal 0. Since relay 1F is deenergized, lamp R of signal 1 will display a steady indication.

When the train on track X enters section 2T, lamp R of signal 2 will display a steady indication on account of relay 2F being deenergized. When the train enters section 1T, lamp R of signal 1 will also display a steady indication on account of relay 1F being deenergized. When the train leaves section 2T, lamp Y of signal 2 will display a steady indication on account of relay 2F still being deenergized.

From the foregoing description and the accompanying drawings, it follows that in apparatus embodying my invention in railway signaling for intersecting tracks, signals for each of the tracks will display a flashing green, yellow or red indication if the other track is unoccupied adjacent the intersection, but will display a steady green, yellow or red indication if the other track is occupied adjacent the intersection.

Although I have herein shown and described only one form of railway signaling embodying my invention, it is understood that various changes and modifications may be made therein within the scope of the appended claims without departing from the spirit and scope of my invention.

Having thus described my invention, what I claim is:

1. In control means for railway signaling for two intersecting railway tracks, including a signal for each of said tracks for governing trains on the corresponding track approaching the intersection, the combination comprising, a traffic control device for each of said signals, and means controlled by each of said control devices in response to a train on the corresponding track approaching the intersection for controlling the associated signal to display an intermittent indication if there is no train on the other of said tracks within a given zone adjacent the intersection and for controlling the associated signal to display a steady indication if there is a train on the other of said tracks within a given zone adjacent the intersection.

2. In control means for railway signaling for two intersecting railway tracks, including a given signal for a given one of said tracks for governing traffic movements on said given track approaching the intersection, the combination comprising, a traffic circuit for said signal, and means

controlled by said traffic circuit in response to a train on said given track approaching within a given distance from said signal for controlling said signal to display a steady indication if the other track is occupied by a train within a given zone adjacent the intersection and for controlling said signal to display an intermittent indication if the other track is unoccupied within said given zone adjacent the intersection.

3. In control means for railway signaling for two intersecting railway tracks, including a given signal for a given one of said tracks for governing traffic movements on said given track approaching the intersection, the combination comprising, a flasher relay, a traffic responsive circuit closed only if said given track is occupied within a given zone adjacent the intersection and if the other track is unoccupied adjacent the intersection for energizing said flasher relay, and means including a contact of said flasher relay for controlling said signal.

4. In control means for railway signaling for two intersecting railway tracks, including a given signal for a given one of said tracks for governing traffic movements on said given track approaching the intersection, including signal control means responsive to a train on said given track approaching said given signal for controlling said given signal to display a given indication for directing a train to proceed over the intersection if there is no train on the other track adjacent the intersection, the combination comprising, a flasher relay, a circuit closed only if said other track is unoccupied within a given zone adjacent the intersection for energizing said flasher relay, and means comprising a contact of said flasher relay for periodically interrupting said given indication if said flasher relay is energized.

5. In control means for railway signaling for two intersecting railway tracks, including a given signal for a given one of said tracks for governing traffic movements on said given track approaching the intersection, including signal control circuit means for normally controlling said signal to display a stop indication but responsive to a train approaching within a given distance from said signal for controlling said signal to display a second indication for directing traffic movements toward the intersection if the other track is unoccupied within a given zone adjacent the intersection, the combination comprising, a flasher relay, a circuit controlled by a train approaching said signal for energizing said flasher relay only if said other track is unoccupied adjacent the intersection, and means controlled by said flasher relay for periodically interrupting said signal control circuit means.

6. In control means for railway signaling for two intersecting railway tracks, including a given signal for a given one of said tracks for governing traffic movements on said given track approaching the intersection, including signal control means for normally controlling said signal to display a steady stop indication, the combination comprising, a control circuit closed in response to a train approaching said signal if said other track is unoccupied adjacent the intersection, and means including said control circuit for controlling said signal to display an intermittent indication for directing a train approaching within a given distance of said signal to proceed over the intersection if said other track is unoccupied adjacent said intersection and for controlling

said signal to display an intermittent stop indication from the time the train passes said signal until it has gone a given distance beyond said intersection if said other track is unoccupied adjacent the intersection.

7. In control means for railway signaling for two intersecting railway tracks, including a given signal for a given one of said tracks for governing traffic movements on said given track approaching the intersection, including a signal control relay which becomes energized in response to a train approaching said signal for controlling said signal to display a steady stop indication or a steady second indication for directing traffic movements over the intersection according as said signal control relay is deenergized or is energized if a train is approaching said signal while said other track is occupied adjacent said intersection, the combination comprising, a control device energized in response to a train approaching said signal if said other track is unoccupied adjacent said intersection, and means controlled by said control device in its energized condition for characteristically modifying the

stop or said second indication displayed by said signal.

8. In control means for railway signaling for two intersecting railway tracks, including a given signal for a given one of said tracks for governing traffic movements on said given track approaching the intersection, including a signal control relay which becomes energized in response to a train approaching said signal for controlling said signal to display a steady stop indication or a steady second indication for directing traffic movements over the intersection according as said signal control relay is deenergized or is energized if a train is approaching said signal while said other track is occupied adjacent said intersection, the combination comprising, a control device energized in response to a train occupying a given zone of said given track if a given zone of said other track is unoccupied, and means controlled by said control device in its energized condition for periodically interrupting the stop or said second indication displayed by said signal.

GEORGE R. PFLASTERER.
